CLAIM

The ornamental design for a motorcycle helmet, as shown and described.

DESCRIPTION

The patent or application file contains at least one drawing executed in color. Copies of this patent or patent application publication with color drawing(s) will be provided by the Office upon request and payment of the necessary fee.

1. Motorcycle helmet

1.1: Front Perspective

1.2: Front

1.3: Back

1.4: Back Perspective

1.5: Left

1.6: Right

1.7: Top

The evenly-spaced broken lines depict portions of the motorcycle helmet that form no part of the claimed design.

1 Claim, 7 Drawing Sheets
